10 Claims. (Cl. 66—1)

1

This invention relates to methods of and apparatus for restoring to original condition a knitted fabric one loop of which has become enlarged or has been "pulled" accidentally in the handling of the fabric after the knitting operation has been completed.

In the manufacture of light weight knitted fabrics, particularly in the manufacture of sheer fabrics utilized in the manufacture of stockings, as for instance those well known fabrics generally known as 45 gauge 30 denier, 51 gauge 30 denier, or 51 gauge 15 denier, a relatively light or fine strand of thread or yarn is employed, for instance a strand of nylon, silk or rayon, or of mixtures of these, with or without other materials. The strands or threads of yarn so employed have great tensile strength and may not be easily broken but, after having been incorporated in a knitted fabric such as a stocking, the "pulling" of a thread may very easily occur for any one of a number of reasons, even while being handled in the most careful manner by a skilled operator. As a result of such a "pulling" operation a loop of the knitted fabric may be greatly enlarged without being broken, the material added to one loop by the pulling being withdrawn from the adjacent loops on both sides of the pulled loop, these adjacent loops being thereby reduced. As a result of the reduction of the adjacent loops, which extend in a rectilinear series with the pulled or enlarged loop at an intermediate point, two additional series of normal loops, disposed parallel to and upon opposite sides of the elongated series of reduced loops, are drawn laterally into closer relationship.

Because of the fact that one loop has been drawn out of the plane of the fabric and has thereby been rendered conspicuous, and further because of the drawing together into abnormally close relationship of the two parallel series of loops previously spaced apart, it becomes obvious at a glance, to one inspecting the fabric, that it is defective. The salability of such an article is sharply impaired. In many knitting mills the output of salable sheer fabrics is substantially reduced and the cost of production of marketed fabrics greatly increased, by this accidental "pulling" of threads, despite the exercise of all reasonable precautions. It is possible to reclaim and render marketable the greater proportion of the knitted goods which have one or more pulled threads and which would otherwise necessarily be rejected and wholly lost, by restoring the fabric to its original condition, the restoration being accomplished manually by acting upon each of the

2

loops of fabric adjacent the "pulled" loop in such manner as to enlarge the reduced loops at the expense of the pulled loop, withdrawing material from the pulled loop and causing it to be included in the reduced loops so that eventually all of the loops, including the formerly enlarged loop and the formerly reduced loops, are all of normal and equal size.

The present invention relates to an improved method and to an improved apparatus for thus restoring to original condition an area of a knitted fabric which has been rendered unsightly and defective by the pulling of a loop and whereby the operation of restoration may be accomplished more accurately and more rapidly than heretofore, a very substantial proportion of the cost of restoring knitted fabrics being eliminated.

Essentially the apparatus is designed and constructed in such manner as to enable one engaged in a restoration operation to rapidly deliver a series of light blows against the opposite, shortened reaches of each of the reduced loops, each blow slightly deflecting or displacing laterally the thread reach which is struck, such deflection causing some material to be withdrawn from an adjacent loop and added to the reduced loop thus contacted. That area of the fabric which includes the pulled and reduced loops is maintained under light tension during the operation of restoration, it being necessary to maintain this portion of the fabric in a stretched, plane condition in order to successfully perform the process. By striking, in succession, each reach of each of the reduced loops disposed upon one side of the pulled loop a number of times while the fabric is under tension, and repeating the operation as many times as may be necessary, material is withdrawn from the pulled loop and is added to all of the reduced loops located on that side, to the end that, in a relatively short time, all of such reduced loops have been restored to their original sizes and the size of the pulled loop greatly reduced. The operation is then repeated upon the opposite side of the pulled loop, the remaining excess material of the pulled loop being caused to creep or move into the reduced loops on that side, each of the deflecting blows having been directed away from the pulled loop.

In order to strike each reach of a reduced loop several deflecting blows in rapid succession and to progressively act in this manner upon successive loops a special instrument is provided, this instrument comprising a circular series of work engaging or impact elements and means mounting said members in such manner that they may

be revolved bodily about an axis, the outer ends of the elements being disposed in a common plane and in a circle. Power means is provided for rotating the mounting so as to move the elements which it carries at a desired speed. The outer end surfaces of the impact elements are sloped rearwardly, having in mind the direction in which they are moved, so that no such element may catch or snag a thread and thus further injure, rather than restore, the fabric being acted upon.

The details of construction of the implement comprising the impact or work engaging elements and the rotatable support or mounting therefor may be varied substantially without departure from the invention but I prefer a design in which the impact elements are of metal and comprise relatively thin and somewhat springy or resilient arms which extend outwardly from the mounting and the smooth work engaging ends of which are located in a circle concentric with the axis of the mounting and in a common plane. With an instrument such as described an experienced operator may bring the rapidly moving work engaging surfaces of the impact elements very accurately into contact with the fabric at a selected point and, by advancing it while maintaining the circle of work engaging ends of the work engaging members in a plane, can accurately cause the instrument to deliver light repeated deflecting blows to successive threads disposed in a straight line along the fabric. In other words, a displaced looped thread may be struck repeated light blows at a number of points disposed in a straight line by drawing the instrument across the surface of the knitted fabric, and a single thread thus acted upon and caused to creep, as it were, through the fabric, withdrawing a desired length of material from the pulled loop and adding it in accurate proportions to several reduced loops.

The work engaging members of the apparatus may be fabricated of any suitable material, steel being preferred, but these elements may be formed of plastic material, animal bristles, fiber, or, in fact, any material which can be fashioned into elongated, relatively thin, smooth and preferably resilient elements. The mounting means for the work engaging elements may be varied widely without departure from the invention although I prefer to mount the inner ends of the elements in a small metallic hub member which is, in turn, supported upon a shaft which may be rapidly rotated by a suitable manual or power operated means.

In the accompanying drawings there is illustrated one embodiment of the apparatus which has been successfully employed in carrying out the process and a number of figures of diagrammatic character are provided in order to show how the device is employed in the elimination of a loop pulled from the body of a knitted fabric.

In the drawings:

Figure 1 is a perspective view of the implement as it will appear when held in one hand of the operator while being used, the operator's other hand encircling a mending cup over which the fabric to be repaired has been stretched;

Figure 2 is an axial section through the implement;

Figure 3 shows, on a relatively large scale, a small area of a knitted fabric, such for instance as a portion of a sheer stocking, a "pulled" loop being shown, likewise a number of reduced loops, these loops being shaded, the fabric shown being thus defective and needing restoration with the

aid of the implement shown in Figures 1 and 2;

Figure 4 is a section on line 4—4 of Figure 3;

Figure 5 is a view similar to Figure 3, showing the same area of fabric, the fabric, however, having been placed under tension on the mender's cup, or in some other manner, the defective portion having been modified somewhat because of the applied tension;

Figure 6 shows the same area of fabric after the restoration operation has been partially completed; and

Figure 7 shows this fabric after the restoration operation has been fully completed.

An enlarged plan view of a small section of knitted fabric is shown in Figure 7. This fabric is in its original, as knitted, condition, having been restored to perfect condition after having been damaged by the pulling of a thread, by the applicant's method and with the aid of his implement. As previously stated, the yarn employed in the original fabrication of the fabric may be of any suitable composition and the denier and gauge may vary widely, the improved method and instrument being applicable to all weights and grades of knitted fabrics. It may be said that the fabric shown in Figure 7 comprises three courses or rows of loops, an upper row the individual loops of which are indicated at *a*, *a'* through *a'*, an intermediate series of loops indicated by *b*, *b'* through *b'* and a lower series of loops indicated by *c*, *c'*, through *c'*. The same piece of fabric is shown in Figure 3, a central loop of the *b* series, however, having been greatly enlarged by a "pulling" operation, this loop being indicated at *b*⁴, and the loops *b'*, *b*², *b*³ and *b*⁵ being shown to be greatly reduced, material having been pulled or withdrawn from these loops and incorporated in the enlarged loop *b*⁴.

In order to restore the fabric to its original condition, as shown in Figure 7, that area which includes the enlarged and reduced loops which have resulted from the pulling out of a loop, is first placed over the open mouth of a mending cup in the manner indicated in Figure 1 and the operator applies one hand in such manner that this relatively small area of the fabric is placed under light tension in all directions. As a result of this tensioning a small hole *h* will appear immediately adjacent the base of the pulled loop *b*⁴. To one side of the small hole *h* (to the left, Figure 5), the reduced loops *b*³, *b*² and *b*' are shown to have been somewhat enlarged and to the other side of the hole *h* and the pulled loop *b*⁴ the loops *b*⁵, *b*⁶ and *b*⁷ have been contracted or reduced. In other words, the pulled loop is now approximately at the midpoint of a rectilinear series of loops which are of reduced size and very similar in appearance. In order to withdraw the excessive thread length contained in the enlarged loop *b*⁴ and cause this material to distribute itself through the several reduced loops the implement illustrated in Figures 1 and 2 is used.

This instrument comprises essentially a core or mounting 10 having extending outwardly therefrom a plurality of work engaging elements 11, the core being mounted upon the end of a shaft or spindle 12 and the outermost or work engaging tips of the elements 11 being disposed along the arc of a circle centered on the axis of the spindle 12. The material of which the mounting 10 is fabricated may be varied widely, likewise the material of which the elements 11 are formed, the manner of attachment of these elements 11 to the hub 10, and even the overall shapes of the elements 11 can be varied within

limits. In every instance, however, the outer work engaging end surface of each element 11 will be smooth, preferably highly polished, and will be disposed at an angle to a radius passing through the tip of that element, being sloped or inclined rearwardly, having in mind the direction of rotation of the implement when it is in use. Thus in Figure 1 the implement is to be rotated in the direction of the arrow w and each of the elements 11 is curved rearwardly for reasons which will become more apparent when its use is more particularly described.

With the fabric under tension, as shown in Figures 1 and 5, the operator will first position the implement in such manner that the tips of elements 11 will, when the hub is rotated, successively contact the collapsed loop b³, striking loop b³, for instance, upon its opposite reaches 20 and 21, reach 20 being deflected from the position in which it is shown in full lines in Figure 5 to the position in which it is shown in dotted lines in that figure, this portion of loop b³ being lengthened, the material added to its length being withdrawn from the elongated or pulled loop b⁴. The operator, after having brought the tips of a number of the elements 11 of the rotating implement successively into contact with the reaches 20 and 21 of the reduced loop b³, will draw the implement toward himself or herself while maintaining the tips of elements 11 in the same plane so that the work engaging end surfaces of elements 11 will next engage reach 21 of loop b³, deflecting and lengthening this portion of loop b³. Thereafter the implement will be further moved horizontally and in the same plane so that the end surfaces of elements 11 successively engage and impose repeated blows upon loops b² and b' at points 22, 23, 24 and 25 respectively.

The effect of each series of impacts of the work engaging elements upon the reduced loops is to move those portions of the loops thus engaged away from the pulled loop b⁴ and to thus increase the reduced loops in size while withdrawing material from the pulled loop. If a single movement of the implement outwardly from the hole h across all of the reduced loops does not have the effect of completely restoring the reduced loops to normal size upon that side of the hole the operation will be repeated and, by reason of the nature of the implement, the work engaging tips of elements 11 together defining a plane, the operator may precisely repeat the initial operation, the successive reaches of the reduced loops previously engaged by the implement being again engaged and similar forces applied thereto and to the fabric.

The operation has the general aspect of a brushing operation, the forwardly facing surfaces of the elements 11 striking and sliding over each contacted section of thread, thus tending to enlarge the reduced loops and restore them to normal size, increase in size of the several reduced loops being at the expense of the enlarged loop b⁴, which gradually loses size. When the series of reduced loops have been fully restored upon one side of the central hole and pulled loop b⁴, as shown in Figure 6 of the drawings, the operator will either turn the mending cup 180° to reverse the fabric, or will reverse the implement, it being easier and simpler to reverse the fabric. After this has been done the implement may be used exactly as previously described to enlarge the remaining aligned loops which have previously been reduced, being moved, on each working

stroke, away from the hole h and (generally) toward the operator. When such enlargement has been fully effected the pulled loop b⁴ will have been reduced to normal size so that the fabric will then appear as it is illustrated in Figure 7, the fabric not indicating in any manner the fact that it has been restored after injury.

The implement, in the hands of a skilled operator, may be used with great facility and in a few seconds time all trace of a pulled loop may be removed and the fabric restored to its original condition. As has been previously explained, the precise details of construction of the implement may be varied to suit the materials upon which it is to operate. An instrument found to be entirely satisfactory in operation comprises a hub of metal and a plurality of thin steel elements 11 shaped as shown in Figure 1 of the drawings, the elements being .018 inch in diameter. In this particular instrument the elements 11 extend outwardly from the periphery of the hub member 10 for a distance of one-half inch and the diameter of the hub is five-eighths of an inch. The instrument is revolved by mechanical power taken from a geared down electric motor, the motion of the rotor of the motor being communicated to the spindle 12 by means of a flexible shaft enclosed within the flexible tube indicated at T in the drawings, the source of power being indicated at M. The motor and its gearing are preferably so designed that the implement is revolved at an angular speed of approximately 400 revolutions per minute, but higher or lower speeds of rotation are permissible.

Each of the elements 11 of the implement is self sustaining in character in that it supports itself and generally maintains its shape when at rest or in motion. The circular path along which the work engaging faces of the implement move when the implement is in use is therefore a definite one, permitting the accurate positioning of the implement relatively to the work.

The width of the work engaging face of each element should be no greater than the width of a normal course of the fabric upon which the implement is being used in a normal manner, otherwise the undamaged loops of courses of the fabric adjacent the damaged course being corrected may be disturbed and the desired result not realized. The work engaging face of an element .018 inch in diameter naturally cannot exceed this dimension in width and actually will be substantially less when the fabric is under tension and the instrument pressed lightly against it. When the loop diameter of the damaged course of the fabric being repaired is quite small it may be desirable to reduce the effective widths of the work engaging faces of the implement and to thus avoid the possible disturbance of the undistorted adjacent courses of the knitted fabric. The selection of elements of the proper dimension for the specific purpose at hand may be easily accomplished. It is well known that the diameters of the loops of knitted hosiery of conventional character vary between .0156 inch and .0312 inch, the most common loop diameters being .020 inch (15 denier) and .021 inch (30 denier), and for restoring pulled threads in knitted fabrics of this character the work engaging needle of circular cross section and having a diameter of .018 inch will perform in an eminently satisfactory manner. For very fine work the width of the work engaging face of the element may be still further narrowed by reducing the diameter of the work engaging element.

In certain instances it may be desirable to subject the area of fabric from which a loop has been "pulled" to a moist atmosphere, for instance to air containing steam or vapor, so as to lubricate the thread. Lubrication of the thread in this manner facilitates its movement under the action of the implement. Needless to say, the method and apparatus are applicable to both dyed and natural fabrics. In the event that an electric motor is not available hand or foot power may be communicated to the implement to rotate it, and in some instances it may be preferred to operate the instrument in this manner. The desired result may be obtained with the aid of instruments of the type described, in which the radiating elements 11 are longer or shorter than those shown and herein described, depending upon the nature of the work to be accomplished.

In one embodiment of the implement, found to be eminently satisfactory in actual use, the elements 11 are curved uniformly, the radius of curvature being about one-half inch. If desired, the work engaging elements may be detachably secured to the hub of the implement, so that elements of different kinds may be employed with a common hub. The member 10 may, for instance, be formed in two parts and the inner ends of elements 11 clamped between these parts, thus making these elements readily interchangeable so that a damaged element may be quickly replaced or one set easily substituted for another when the implement is to be applied to different types of fabrics.

Having thus described the invention, what is claimed as new and desired to be secured by Letters Patent is:

1. Apparatus for restoring to original condition a knitted fabric one loop of which has become enlarged and adjacent loops reduced, comprising, in combination, a spindle adapted to be rotated about its longitudinal axis, a hub fixed upon the spindle and rotatable therewith, and a circular series of self sustaining work engaging elements mounted upon said hub, said elements being adapted to successively engage the work when the hub is rotated, the work engaging surfaces of said elements at the outer ends thereof facing forwardly and outwardly and being smooth and no wider than a normal course of the fabric to be restored.

2. Apparatus for restoring to original condition a knitted fabric one loop of which has become enlarged and adjacent loops reduced, comprising, in combination, a circular series of self sustaining work engaging elements, and means mounting said elements for movement about an axis with the leading surfaces of the outer end portions of said elements disposed in a circular series to successively contact and deflect a thread of a knitted fabric, said leading surfaces being no wider than a normal course of the fabric to be restored and being sloped so as not to catch any thread.

3. A brush-like implement for restoring "pulled" threads in knitted fabrics comprising a circular series of resilient bristle-like elements, means mounting said elements about a common axis with the outer ends thereof disposed in a circle centered on said axis, and second means for rotating said first mentioned means in one direction of rotation, the outer end portion of each such element being sloped rearwardly so as not to catch any thread which it may engage and being of no greater width than the width of a normal course of the knitted fabric to be acted upon.

4. Apparatus for restoring pulled threads in knitted fabric comprising a circular series of angularly spaced elements having terminal work engaging surfaces of less width than the distance between two normal courses of the fabric to be restored and similarly sloped with respect to radii passing therethrough, respectively, and means supporting said elements for rotation in a plane and about the axis of said circular series.

5. Apparatus for restoring pulled threads in knitted fabric comprising a hub adapted to be rotated about a fixed axis and a series of radiating elongated resilient work engaging elements supported on said hub and having smooth forwardly facing rearwardly and outwardly sloping work engaging faces disposed in a common plane and at the same distance from said axis, each such face being of less width than a normal course of the fabric to be restored.

6. A device for use in the textile industry in restoring to normal condition an area of a knitted fabric a course of which has been rendered defective by the pulling and enlargement of a loop and the reduction of loops adjacent to said enlarged loop, said device comprising a plurality of work engaging elements each having a smooth elongated, arcuate work engaging surface, said work engaging surfaces being spaced apart, arranged in a circular series about a common center, and disposed substantially in a plane, the effective width of each such surface not exceeding the width of a normal course of the fabric to which the apparatus is to be applied, and means mounting said elements for rotation about an axis passing through the common center about which said surfaces are arranged and normal to the plane in which they are substantially disposed whereby, when said means is rotated, said work engaging surfaces may be caused to successively engage the work.

7. A device for use in the textile industry in restoring to normal condition an area of a knitted fabric a course of which has been rendered defective by the pulling and enlargement of a loop and the reduction of loops adjacent to said enlarged loop, said device comprising a plurality of work engaging elements each having a smooth elongated work engaging surface, said work engaging surfaces being spaced apart, arranged in a circular series about a common center and disposed substantially in a plane, the effective width of each such surface not exceeding the width of a normal course of the fabric to which the apparatus is to be applied and each such surface being sloped so as to engage and deflect without catching any thread disposed in its path of movement, and means mounting said elements for rotation about an axis passing through the common center about which said surfaces are arranged and normal to the plane in which they are substantially disposed whereby, when said means is rotated, said work engaging surfaces may be caused to successively engage the work.

8. A device for use in the textile industry in restoring to normal condition an area of a knitted fabric a course of which has been rendered defective by the pulling and enlargement of a loop and the reduction of loops adjacent to said enlarged loop, said device comprising a plurality of elongated, resilient, self-sustaining wire-like work engaging elements each having a smooth work engaging surface, said work engaging surfaces being spaced apart, arranged in

a circular series about a common center and disposed substantially in a plane, the effective width of each such surface not exceeding the width of a normal course of the fabric to which the apparatus is to be applied and each being elongated in the plane in which said surfaces are substantially disposed and curved to present to the work a surface which is transversely and longitudinally convex so as to engage and deflect without catching any thread disposed in its path of movement, and means mounting said elements for rotation about an axis passing through the common center about which said surfaces are arranged and normal to the plane in which they are substantially disposed whereby, when said means is rotated, said work engaging surfaces may be caused to successively engage the work.

9. Apparatus for restoring to original condition a knitted fabric one loop of which has become enlarged and adjacent loops reduced, comprising, in combination, a spindle adapted to be rotated about its longitudinal axis, a hub fixed upon the spindle and rotatable therewith, and a circular series of resilient, self-sustaining metallic wire-like work engaging elements mounted upon and radiating from said hub, the work engaging surfaces of said elements at the outer ends thereof facing forwardly and outwardly and being smooth and no wider than a normal course of the fabric to be restored.

10. The method of restoring to original condition a distorted course of a knitted fabric one loop of which has become enlarged by the incorporation therein of material withdrawn from adjacent loops which have for this reason been reduced, comprising, placing an area of the fabric which includes the enlarged and reduced loops under light tension and, while maintaining the fabric under tension, withdrawing material from the enlarged loop and adding it to the reduced loops until all are restored substantially to normal size, by striking a distorted

loop located closely adjacent the enlarged loop a series of relatively light rapidly repeated blows applied in a direction longitudinally of the distorted course and away from the enlarged loop by impact members the effective widths of the work engaging surfaces of which do not exceed the width of a normal course of the fabric, thereafter similarly applying a series of similarly directed relatively light and rapidly repeated blows in succession to those remaining distorted loops of the course which are located upon the same side of the enlarged loop as the loop first engaged and thereby restoring to normal size all distorted loops of the course upon that side of the enlarged loop and reducing the enlarged loop, and thereafter similarly acting upon in succession the distorted loops of that portion of the distorted course which are disposed upon the opposite side of the enlarged loop.
